UNITED STATES PATENT OFFICE.

EUGENE GREEN, OF SAN MARCOS, TEXAS.

WRENCH.

985,028.

Specification of Letters Patent. Patented Feb. 21, 1911.

Application filed April 28, 1910. Serial No. 558,140.

To all whom it may concern:

Be it known that I, EUGENE GREEN, a citizen of the United States, residing at San Marcos, in the county of Hays and State 5 of Texas, have invented certain new and useful Improvements in Wrenches, of which the following is a specification.

My invention relates to wrenches, and more particularly to those that may be trans- 10 formed from a pipe to a nut wrench.

The object of the invention is to provide a simple, practical and effective locking device for a wrench of the character above described, whereby the movable jaw is accurately and instantaneously adjusted and locked in a rigid position in respect to the stationary jaw of the wrench, thereby adapting 15 the latter to pipes and nuts of various sizes and shapes.

Another object of the invention is to locate the operative portion of the lock in such a position upon the movable jaw that the same will not interfere with the work to be operated upon and will always be in 20 convenient position to be readily operated when it is desired to adjust the jaws in their proper position in respect to one another.

A further object of the invention is to provide detachable means for transforming 25 the gripping surfaces of the jaws of the wrench, whereby the latter may be applied to pipes and nuts with like facility and effectiveness.

Briefly stated the invention consists of a 30 suitable shank, the upper end of which is provided with the usual fixed jaw, the lower gripping surface of said jaw being provided with ratchet teeth, ratchet teeth formed on the inner edge of said shank, a movable jaw 35 slidably arranged upon said shank and having ratchet teeth formed upon the gripping portion thereof, a locking device located within a suitable cavity formed within the movable jaw and adapted for engagement 40 with the ratchet teeth formed upon the edge of the shank, means for operating said locking device, and plates provided with ratchet teeth which correspond with the ratchet teeth formed on the engaging gripping surfaces 45 of the jaws of the wrench for the purposes previously described.

Other objects and advantages will be apparent from the following description and it will be understood that changes in the 50 specific structure shown and described may be made within the scope of the claim with-

out departing from the spirit of the invention.

In the drawings: Figure 1 is a side elevation of the complete invention, showing the 60 stationary jaw and handle in elevation. Fig. 2 shows a side elevation of the wrench with a removable jaw partially in a section, Fig. 3 is a transverse section of the movable jaw taken on the line $x-x$ of Fig 1, Fig. 65 4 is a plan view of the operating lever and eccentric attached thereto forming a portion of the locking device, Fig. 5 is an edge view of the detachable plates employed for providing a nut wrench, Fig. 6 is a combined 70 side elevation and sectional view showing a fragmentary part of the wrench and illustrating a modification of the invention. Fig. 7 is the upper end of the nut wrench showing the serrated plates in a reverse position. 75

Referring to the drawings, 1 represents a shank which is preferably rectangular in cross section, to the lower end of which is attached the usual handle 2, the upper end of said shank terminating in the head 3, which 80 forms the fixed jaw for the wrench, the lower gripping edge of the jaw being provided with ratchet teeth 4. The inner edge 5 of the shank 1 of the wrench is provided with ratchet teeth 6, which extend a suitable distance along the length of the shank, which 85 teeth are adapted to coöperate with the locking device carried by the movable jaw in a manner hereinafter to be described.

The movable jaw 7 is slidably located 90 upon the shank 1 by means of the loop portions 8 forming an integral part of said jaw and through which the said shank freely passes, the upper gripping surface of said movable jaw being provided with ratchet 95 teeth 9 which are formed in the opposite direction to the ratchet teeth 4 of the fixed jaw 3, whereby pipes or other objects of irregular contour may be properly gripped for turning or manipulating the same. 100

Formed in the movable jaw 7 immediately opposite the ratchet teeth 6 on the edge of the shank 1 is a cavity 10, and movably fixed within said cavity is a cam lever 11, the lower convex engaging surface of which is 105 provided with ratchet teeth 12, which are adapted to coöperate with the ratchet teeth 6 formed on said shank, the upper or long arm 13 of said cam lever projecting a suitable distance within said cavity and out of 110 contact with the ratchet toothed edge of the shank. Secured to the movable jaw 7, ad-

adjacent to the edge of the shank 1 and above the cavity 10 formed therein is one end of a leaf spring 14, the opposite or free end of said spring projecting downwardly and extending within the cavity and against the long arm 13 of the cam lever 11, whereby the lower engaging end of the latter is held in its normal position or in contact with the teeth 6 formed on the shank 1, in which position of the cam lever the movable jaw may be freely moved or adjusted toward the stationary jaw, but is prevented from being moved in the opposite direction upon the shank of the wrench. Also located within the cavity 10 of the movable jaw 7 and immediately in the rear of the long arm 13 of the cam lever 11, and in contact with the same is an eccentric 15, which is provided with a sleeve 16 projecting at right angles therefrom. The sleeve 16 freely passes through one wall of the movable jaw adjacent the cavity 10 formed therein and screwed into the said sleeve and through the eccentric forming a part thereof is a screw 17, the head 21 of which comes in direct contact with the outer edge of said sleeve and projects beyond that side of the movable jaw 7, whereby the eccentric 15 is rigidly secured to the screw, but rotatable within the cavity 10. The hand operated lever 19 is located to one side of the movable jaw and is provided with an opening 18 which snugly receives the head 21 of the screw 17, a pin 20 being passed through said head and lever 19 for rigidly connecting the parts, whereby the eccentric or enlarged edge thereof will be brought into connection with the upper end of the cam lever 11 when the lever 19 is elevated for releasing the lower engaging end of the cam lever from its locked position with respect to the ratchet toothed edge of the shank 1.

From the foregoing description it will be seen that when it is desired to apply the wrench to a pipe or other object, the hand operated lever 19 is elevated, in which operation the eccentric 15 will be brought into engagement with the upper end of the cam lever 11, thus moving the lower toothed end 50 of said lever out of contact with the teeth 6 formed upon the shank and permitting the movable jaw to be freely released to be moved in a downward direction or from the stationary jaw 3 of the wrench. After the jaws have been properly separated the hand operated lever 19 may be released and the movable jaw adjusted toward the stationary jaw without further manipulation of the locking device, the teeth 12 formed on the lower end of the cam lever riding over the ratchet teeth 6 formed on the shank.

There are many instances when it is desired to apply a wrench of this character to nuts or other rectangular objects without in any way defacing or injuring the same, and

for this purpose detachable plates are employed in connection with the gripping surfaces of the jaws of the wrench. Referring particularly to Fig. 5 of the drawings, two plates 22 are employed, which are similarly constructed, the width and length of which correspond to the width and length of the gripping surfaces of the stationary and movable jaws of the wrench, and formed on one side of said plates are ratchet teeth 23, which correspond in size and shape to the shape of the teeth formed on said jaws, the opposite sides of said plates being smooth and flat for engagement with the nut or object to be operated upon. Secured to the opposite edges of the plates adjacent to the ends thereof are flat springs 24, the free ends of which project a suitable distance from the toothed surfaces of the plates and are adapted to yieldingly contact with the opposite flat sides of the jaws of the wrench adjacent to the toothed gripping edges thereof, whereby said plates are held in their proper position in respect to said jaws and further are prevented from moving in a longitudinal direction in respect to the jaws when the same are applied to a nut or other object, said movement of the plates being prevented by the engagement of the ratchet teeth formed on the plates and the gripping surfaces of the jaws of the wrench.

From the foregoing description it will be seen that the plates 22 may be readily removed from their interlocked position in respect to the jaws when it is desired to use the tool as a pipe wrench, the locking device of the wrench being effective and applicable in both instances.

In Fig. 6 I have shown the application of the invention in which the movable jaw is provided with a cam lever 11 having a lower cam engaging end which is similar to the construction previously referred to. In this construction the cam 15 projects in a downwardly direction and is normally in contact with the upper end of the long arm 13 of the lever 11 and the spring 14 is fixed to the lower portion of the movable jaw 7 and projects inwardly to come in contact with the cam lever 11 below its pivotal connection.

In Fig. 7, I have shown the wrench with smooth engaging jaws to be applied to nuts, in which instance the serrated detachable plates are attached thereto for the application of the wrench to pipes. In this arrangement the yielding arms 24 will be arranged in a reversed position to those shown in Fig. 5 and located within suitable recesses formed for their reception in the opposite sides of the jaws of the wrench. This construction and arrangement is very desirable for the reason that it is sometimes necessary to work on nuts in very close places and consequently the work would not be interfered with by the detachable plates.

In the construction last referred to it will be seen that when the wrench is transformed into a pipe wrench the smooth surfaces of the plates 22 will be in contact with the engaging flat surfaces of the jaws of the wrench, with the serrated portions of the plates facing one another and adapted for ready application to a pipe.

What is claimed is:

- 10 In a wrench the combination with a stationary jaw and shank, of a movable jaw slidable upon said shank, ratchet teeth formed upon the latter, a cam lever having ratchet teeth formed on the lower convex 15 end of the same and adapted for engagement with the ratchet teeth formed upon the shank, an eccentric located within the cavity adjacent to the upper end of said cam lever and normally in contact therewith, a sleeve 20 forming a part of said eccentric and passing freely through an opening formed through one side of the jaw, a screw through the said sleeve and eccentric and passing through a suitable opening formed in the

opposite side of the jaw, the head of said screw projecting a suitable distance beyond one side of the wall of the jaw through which it passes and in binding contact with said sleeve of the eccentric, a hand operating lever fixed to the head of the screw for causing the eccentric to be brought into frictional contact with the upper end of the cam lever, and a spring secured to the jaw and having its lower free end located within the cavity of said jaw and in contact with the upper end of the cam lever opposite the eccentric, whereby when the hand operating lever is elevated, the lower engaging end of the cam lever will be moved out of engagement with the ratchet teeth formed on the shank of the wrench.

In testimony whereof I affix my signature, in presence of two witnesses.

EUGENE GREEN.
